FRYING PAN COVER

Homer H. Fair, Modesto, Calif., assignor of one-half to Richard P. Worthen, Modesto, Calif.

Application March 24, 1955, Serial No. 35,179

Term of patent 14 years

(Cl. D44—1)

Fig. 1 is a top plan view of a frying pan cover showing my new design;

Fig. 2 is a side elevational view thereof;

Fig. 3 is a cross-sectional view taken along line 3—3 of Fig. 1; and,

Fig. 4 is a cross-sectional view taken along line 4—4 of Fig. 1.

I claim:

The ornamental design for a frying pan cover, as shown.
